(57) **CLAIM**

The ornamental design for a surgical staple cartridge, as shown and described.

DESCRIPTION

- 4.1: Front view of a surgical staple cartridge
4.2: Back view of the surgical staple cartridge of 4.1
4.3: Left view of the surgical staple cartridge of 4.1
4.4: Right view of the surgical staple cartridge of 4.1
4.5: Top view of the surgical staple cartridge of 4.1
4.6: Bottom view of the surgical staple cartridge of 4.1
4.7: Perspective view of the surgical staple cartridge of 4.1
4.8: Enlarged fragmentary view of 4.1
4.9: Enlarged fragmentary view of 4.3
4.10: Enlarged fragmentary view of 4.4
4.11: Enlarged fragmentary view of 4.5
4.12: Enlarged fragmentary view of 4.6
4.13: Enlarged fragmentary view of 4.7

The broken lines in the drawings are included for the purpose of illustrating portions of the surgical staple cartridge that form no part of the claimed design.
